UNITED STATES PATENT OFFICE.

THEODORE THOMAS, OF NEW YORK, N. Y.

CAR-WHEEL.

SPECIFICATION forming part of Letters Patent No. 292,267, dated January 22, 1884.

Application filed June 15, 1883. (No model.)

To all whom it may concern:

Be it known that I, THEODORE THOMAS, of New York city, in the county and State of New York, have invented a certain new and useful Improvement in Car-Wheels; and I do hereby declare the following to be a full, clear, and exact description of the same, reference being had to the accompanying drawings, which form a part of this specification.

10 The invention is designed to secure elastic qualities for the wheel and increased length of life for the tire, to deaden the sound, and to increase the strength and durability in use, and the simplicity in structure of the wheel as a whole; and it consists of the improved car-wheel hereinafter specifically described and claimed.

In the accompanying drawings, Figure 1 represents a side view of the improved car-wheel, a portion being removed to show more clearly the interior structure, showing a partial section on the lines *w w*. Figs. 2 and 3 are sections on the lines *x x* and *y y*, respectively.

25 Like letters of reference in the several figures represent like parts.

The improved car-wheel consists of a metal casting, *A*, forming the hub and web portion of the wheel, a steel-tire portion, *B*, an intervening series of blocks, *C C*, of some suitable elastic substance, and securing-bolts binding all portions of the wheel together. The casting *A* may be made in any usual way. It is essential, however, that it should have an annular series of recesses or pockets on its circumference, slightly wedge-shaped, opening outward, and separated from each other by radial metal walls. These metal walls are radial projections of the casting *A*, and are marked *aa* in the drawings. The sides of the recesses are formed by the side plates, *b* and *c*, of the casting *A*, and the bottom by the web or wall *d* of the casting *A*. This web or wall *d* may be placed at any suitable depth. The side plate, *b*, extends outward to within clearing distance of the internal diameter of the tire *B*, while the plate *c* is of such diameter as to clear the internal flange, *e*, of the tire. The blocks *C C*, of wood, prepared paper, or other material of sufficient strength, durability, and elasticity, having been prepared of suitable size and shape, are forced into the recesses in

the casting *A*, heretofore described. The radial shape of the recesses and corresponding wedge-shape of the blocks enables me, by driving the blocks in toward the center, to get a very solid and firm seat for them all down the sides of the radial projections, and this without the necessity of very accurate fitting of the blocks to the recesses, as the wedge-shaped blocks find a firm seating when driven far enough. By shrinking or forcing the tire on the blocks that have already been seated in these wedge-shaped recesses I obtain a very solid and substantial wheel. The radial arms 55 are numerous enough, and the recesses correspondingly slight in their convergence toward the center to hold the wedge-shaped blocks firmly in place. This mode of supporting the blocks in these slightly-diverging recesses 60 gives a more elastic and durable wheel.

The steel tire *B* has an internal flange, *e*, which flange, when the tire is in position, bears laterally its entire depth against the sides of the blocks *C C* without touching the 65 sides of the walls or radial projections *aa*, and is flush on the outside with the plate *c*, as shown. The blocks *C C*, which project outward slightly beyond the parts *aa* of the center casting, *A*, are turned, to admit of the tire 70 *B* being forced or shrunk on them, by which forcing or shrinking the said blocks are firmly seated in the recesses, but in such a way that the blocks *C C* form the substantial and only connection between the center casting, *A*, 75 and the tire *B* in the direction of the load, the side plates, *b* and *c*, of the center casting, *A*, being left just free of the adjacent portions of the tire, and the radial walls *aa* being also free of the tire, as shown. A series of bolts, 80 *DD*, passing through the internal flange, *e*, of the tire, and the radial walls *aa*, and the plate *b* of the central casting, *A*, securely holds the 85 different parts of the wheel together.

I do not wish to confine myself to the particular system of flanges and of connecting-bolts shown in the drawings, whereby the central and outer portions of the wheel are secured together. I prefer, however, the form shown in the drawings, for with the arrangement there shown the pressure of the tire-flange proper on the track-rail in operation tends to consolidate and strengthen the wheel as a whole, and by passing the system of bolts 90 95 100

through the metal portions of the wheel only, in contradistinction to passing them through such portions, and also through the wood or paper or other filling, a more durable wheel 5 is obtained.

I am aware that wood, paper, &c., have been used in car-wheels to carry the load; but my arrangement of this cushioning material in a series of small wedge-shaped recesses forming, 10 when the tire is added, a substantial covering and protection for the cushioning material on all sides, produces a simple wheel to manufacture, because the wedge-shaped pieces of cushioning material need not be accurately 15 fitted, for, being driven in, they will somewhere reach a firm seat, which can only be strengthened and consolidated by the shrinking or forcing on of the tire. My arrangement, also enabling me to securely bolt the tire and 20 central portions of the wheel together without passing bolts through any portion of the cushioning material, is, I believe, new in this class of wheels.

What I do claim as new, and desire to secure by Letters Patent, is—

1. As a new article of manufacture, a car-wheel consisting of a central portion having a series of wedge-shaped peripheral recesses,

formed by side plates and by numerous radial cross-arms converging but slightly toward 30 the center, as shown, in combination with a tire portion, and between the two a series of separated and independent blocks of wood, paper, or similar material, seated in the wedge-shaped recesses, as shown, to carry the entire 35 load, substantially as and for the purposes set forth.

2. As a new article of manufacture, a car-wheel consisting of the center portion, A, having side plates, b and c, and numerous radial 40 arms, a a, a series of blocks, C C, of wood, paper, or similar material, and a tire portion, B, all suitably connected, substantially as and for the purposes set forth.

3. As a new article of manufacture, a car-wheel consisting of a center portion, A, having side plates, b and c, and radial arms a a, a series of blocks, C C, of wood, paper, or other suitable material, a tire portion, B, having a flange, e, and securing-bolts D D, passing 50 through metallic portions of the wheel only, substantially as and for the purposes set forth.

THEODORE THOMAS.
